(51) **LOC (10) Cl. 10-05**

(57) **CLAIM**

(52) **U.S. Cl.**

We claim the ornamental design for an alarm unit assembly, alarm unit, and connector, as shown and described.

USPC **D10/106.1**

DESCRIPTION

(58) **Field of Classification Search**

USPC D10/106.1–106.5, 104.1, 106.9
See application file for complete search history.

FIG. 1 is a perspective view of an alarm unit assembly showing our design;
FIG. 2 is a left side view thereof;
FIG. 3 is a front view thereof;
FIG. 4 is right side view thereof;
FIG. 5 is top view thereof;
FIG. 6 is a rear view thereof; and,
FIG. 7 is a bottom view thereof.
The broken lines depict unclaimed environmental subject matter. The broken lines form no part of the claimed design.
